AIRPLANE

Beverly L. Horton and Dorthe A. Horton, both of 306
Rocky Hill Terrace, Van Zandt Place, Fort Worth,
Tex.

Filed June 22, 1959, Ser. No. 56,481

Term of patent 14 years

(Cl. D71—1)

Fig. 2

Fig. 1 is an enlarged perspective view of the interior section for an airplane shown in full lines in Fig. 2; and

Fig. 2 is a perspective view of an airplane embodying our new design.

The dominant features of the design reside in the portions shown in full lines.

We claim:

The ornamental design for an airplane, as shown and described.
